HOLLOW STEM POPPET VALVE

William E. Achor, Willoughby, Ohio, assignor to
 Thompson Products, Inc., Cleveland, Ohio, a
 corporation of Ohio

Application May 8, 1951, Serial No. 225,219

3 Claims. (Cl. 123—188)

1

This invention relates to a poppet valve structure designed for use as an inlet and exhaust valve for internal combustion engines.

Two of the most important problems in valve design are concerned with providing suitable means for cooling the valve body to prevent warping and corrosive oxidation of the valve and also avoiding the formation of coke and varnishes resulting from the high temperature decomposition of fuels and lubricants.

While valves have previously been designed to permit removal of heat from selected areas of the valve surface, these means usually include a relatively thin-walled stem portion, resulting in the reduction of strength in the valve body, and thus increasing the possibility of fracture of the valve.

In the valve assembly of the present invention I have provided means for controlling the amount of heat removal from selected areas of the valve, while at the same time providing a sufficiently strong valve to resist adequately the longitudinal and radial stresses normally occurring in the operation of the valve.

In the valve assembly of the present invention a conventional type of poppet valve is provided with an internal cavity for receiving a coolant, the shape of the cavity being so arranged as to provide differing amounts of heat removal from selected portions of the valve. The cavity within the intermediate stem portion of the valve is made with a larger diameter than the cavity within the upper stem portion of the valve. In one embodiment of the invention the cavity extends from the valve guide-engaging stem portion up into the head portion of the valve. Contrary to ordinary practice, the head portion is not hollowed out in the valve of the present invention but is provided with only a small diameter cavity, the diameter of the cavity in the head being less than the diameter in the stem portion. In other words, the internal cavity of the valve is progressively smaller from the stem portion of the valve upwardly into the valve head.

By providing a varying diameter cavity in the interior of the valve assembly, several distinct advantages may be realized. In the valves in the present invention a stronger section results in the upper portion of the stem because, first, there is an increased wall thickness in that portion of the valve as compared to those valves which employ a constant diameter cavity throughout the stem portion. In addition, this portion operates at a lower temperature, and in many cases cooler than the constant diameter

2

cavity valves or hollow-headed valves, thereby raising the elastic limit of the valve material at the operating temperature.

The valves of the present invention are also designed for the most advantageous heat removal conditions. In hollow-headed valves it is sometimes possible to remove too much heat from the valve head. Cooling the valve head beyond the point necessary decreases the ability of the cooling material, such as metallic sodium, in the valve cavity to pick up sufficient heat in the upper regions of the valve stem from which an adequate amount of heat removable is more critical than it is in the head portion. The small diameter cavity provided in the head portion of the valve of the present invention may extend any desired distance into the valve head and may be of such diameter as to remove a sufficient amount of heat to effect the proper balance between the heat transfer occurring in the head and stem portions.

The largest diameter of the cavity in the valves of this invention occurs in the portion of the valve stem which reciprocates within the valve guide. In this portion of the valve it is permissible to reduce the strength of the valve to attain the more important objective of increasing the amount of heat transfer. The strength of the valve in this region is not a particularly critical consideration since lateral thrust or bending is minimized by the bearing action of the valve guide. In addition, since the existing temperature in the stem portion is relatively low due to the heat transfer in this portion, the yield strength is adequate to resist tensile stresses without deformation.

The stem cavity construction of the valve of the present invention has also the advantage of permitting uniformly controlled flow of heat from the substantially solid valve head to the coolant cavity and subsequently to the valve stem.

It has also been found that less coke formation and varnish formation occurs on the valve stem and associated areas of the valve primarily because although more heat is removed from the upper portion of the valve stem, considerably less heat is removed from the valve head, and the total heat transfer to the valve stem is lower than occurs when using constant diameter cavities or hollow-headed valves. Consequently, lower temperatures occur in the valve guide and the lower portions of the valve stem, thereby reducing the amount of coke and varnish created by the high temperature breakdown of hydrocarbon fuels and lubricants. Since lower tem-

peratures exist in the valve guide and less coking and varnishing occur, the valve stem wear is reduced.

One of the objects of the present invention is to provide a valve assembly with an internal cavity so arranged as to provide optimum conditions of heat transfer for selected areas of the valve.

Another object of the present invention is to provide a poppet valve structure in which the upper valve stem portion is designed to provide adequate cooling, while still being of sufficient strength to resist the stresses in this section of the valve.

Another object of the present invention is to provide a valve structure in which the production of coke and varnish formation are minimized by the design of the stem portion of the valve.

A further description of the present invention will be made in connection with the attached sheets of drawings in which:

Figure 1 is a fragmentary view of an engine assembly illustrating the valve of the present invention in its closed position; and

Figure 2 is a view similar to Figure 1 but illustrating the valve in its open position.

As shown on the drawings:

Reference numeral 10 denotes generally an engine part of an internal combustion engine associated with a combustion chamber in the engine and having a tapered seating face 11 against which the poppet valve becomes seated in its closed position. The poppet valve 12 of the present invention consists of a head portion 13 which includes an annular valve seating surface 14 and a flared neck portion 15 joining the head portion 13 to a stem having a stepped bore and a closed tip end. The stem has an upper stem portion 16 extending from the neck 15, an intermediate stem portion 17 which is arranged to reciprocate within a valve guide member 18, and a solid tip or lower end portion 19.

The solid end of the valve stem has a conventional annular retainer lock groove G near the tip thereof for cooperating with a bead 20 of a retainer lock 21. A conventional valve spring retainer cap 22 is secured on the valve stem by the lock 21.

The poppet valve 12 is biased in its closed position, with the valve seating surface 14 in seating relation with the annular seating face 11 of the engine part by means of a coiled spring 23 acting between the valve guide member 18 and the valve spring retainer cap 22.

The primary feature of the present invention is concerned with the arrangement of the internal cavities within the poppet valve structure. As shown on the drawing, the intermediate region of the valve stem 17 is provided with a cavity 17a of maximum diameter, leaving a thin wall section in the stem portion 17 of the valve. As shown in Figure 2, the larger diameter recess 17a extends up the valve stem 17 a sufficient distance so that the recess 17a is still within the confines of the valve guide 18 when the valve is in its open portion. Alternately, however, the thin stem wall section enclosing the recess 17a can extend above the guide when the valve is open as long as this section is entirely within the guide when the valve is closed and stressed.

In the portion of the valve at the upper stem portion 16 the cavity is reduced in diameter to form a reduced diameter recess 16a in this area. Through this construction a balance is achieved between the amount of transfer required to cool

adequately the upper stem portion 16, while at the same time providing sufficient wall thickness to enable this portion to resist a substantial amount of stress. The cavity 13a in the head portion 17 has the smallest diameter, so that less heat is removed from the head of the valve than is the case where a substantially hollow-headed valve is used.

The cavities of the valve are filled with a coolant material 25 such as metallic sodium, or the like, in the same manner as in ordinary hollow poppet valves of this nature.

While in the drawings I have illustrated an internal cavity having three different dimensions, it will be appreciated that in some cases, to achieve the proper amount of cooling, the cavity 13a may be of the same diameter as the cavity 16a, or possibly larger. However, in each instance the controlling factor is the construction and size of the cavity associated with the upper stem portion 15 as compared with the cavity in the intermediate stem portion 17.

While the various cavities have been illustrated in the drawings as cylindrical in form, it will also be appreciated that the cavities may take various forms, such as a gradual taper from the stem portion to the head portion.

The valve of the present invention may be of a one-piece construction using material such as SAE 2112 steel. If desired, the stem end of the valve can be composed of a wear-resistant alloy such as SAE 3140 steel. It is also within the scope of the present invention to provide selected areas of the valve body with corrosion-resistant jackets, or sheaths, particularly in the vicinity of the neck portion and the valve seating surface. Typical among such alloys are the Stellite alloys containing 63 to 68% cobalt, 27 to 30% chromium, and 2 to 6% tungsten. Suitable corrosion-resistant surfaces can also be welded to the surfaces of the valve body from nickel base alloys having a high degree of corrosion resistance.

It will be understood that modifications and variations may be effected without departing from the scope of the novel concepts of the present invention.

I claim as my invention:

1. An exhaust poppet valve comprising a head portion having a valve seating surface thereon, an intermediate stem portion arranged to reciprocate within a valve guide, an upper stem portion extending from said intermediate stem portion to said head portion, and a solid lower stem portion, said intermediate and upper stem portions having a multi-stepped cavity therein extending from said intermediate stem portion into said head portion said cavity having uniform but different sized diameters on opposite sides of the steps, the diameter of said cavity being larger in said intermediate stem portion than in said upper stem portion, and larger in said upper stem portion than in said head portion.

2. A poppet valve comprising a head portion having a valve seating surface thereon, an intermediate stem portion arranged to reciprocate within a valve guide, an upper stem portion extending from said intermediate stem portion to said head portion, and a solid lower stem portion, said intermediate stem portion, said upper stem portion, and said head portion having extending therethrough a continuous multi-stepped cylindrical cavity of at least three different diameters with the largest diameter cavity in said

intermediate stem portion, and the smallest diameter cavity in said head portion.

3. A poppet valve for reciprocal mounting in a guide which terminates in spaced relation from a valve port, comprising a head portion having a valve seating surface thereon for coacting with said port, an intermediate stem portion arranged to reciprocate within a valve guide, an upper stem portion extending from said intermediate stem to said head, said intermediate stem portion, said upper stem portion, and said head portion having extending therethrough a continuous cavity, said cavity consisting of at least three different diameters, said diameters decreasing stepwise with the largest diameter cavity in said intermediate stem, a correspondingly smaller

cavity in the upper stem portion and the smallest diameter cavity in said head portion, and said largest diameter cavity remaining in the guide throughout the full reciprocal movement of the valve.
